SHOE LAST AND PROTECTOR THEREFOR

Paul S. Jones, Brockton, Mass., assignor to Jones & Vining, Inc., Brockton, Mass., a corporation of Massachusetts

Application April 9, 1938, Serial No. 201,147

3 Claims. (Cl. 12—139)

My present invention is a novel and improved last for use in manufacturing boots and shoes, and includes a novel protector for the top or cone of the last around the recess for the last-holding pin of the jack.

Heretofore it has been customary in making shoe lasts to provide a thimble-holding recess in the top or cone of the last forwardly, and arranged to receive a metal thimble, and also it has been customary to apply one or more protecting layers on the top of the cone thru which the thimble passed so as to aid in protecting the wood of the last during the various strains, blows, and stresses to which the last is subjected during the processes of shoe manufacture, particularly in the heel-nailing and shoe leveling operations.

My present invention is directed to improve and perfect the last protecting construction and to eliminate the necessity for a long and expensive metal thimble, while utilizing one or more layers of last protecting material, which are attached to the top or cone of the last. Such protecting layers may be of any suitable and desirable material, such for example as fibre or leather, which are at present generally employed, and are secured by nails or screws to the wood of the last.

Heretofore these layers have been united by nails or screws attaching them to the last as well also as by the top portion of a metal thimble, which is driven into the thimble hole bored into the last.

By my present invention, which eliminates the thimble heretofore fitted into the last, I employ a metal member, collar, or tubular rivet, which may extend a short distance into the thimble hole, similar in diameter and material to the upper part of the last thimble and fit the same rigidly and permanently thru the protecting layers, thus uniting the layers before they are applied to or attached to the cone of the last, and thus also provide a strong, rigid, metal bearing for the pin of the last jack, which pin may pass thru the metal collar, washer, or tubular rivet and extend loosely into the interior of the wood of the last.

My invention thus eliminates expense to a large degree, rigidly secures the protector layers together, and furthermore provides a bearing at the top of the last hole for the jack pin, permitting the jack pin to be located somewhat freely within the thimble hole and eliminating the lateral strain heretofore thrust upon the wood of the last by the metal thimble, which had to resist all strains and stresses from the jack pin transmit-

ted thru the thimble, and thus tending to breakage of the last.

Thus my invention eliminates the expense of a metal thimble and eliminates also to a large degree the tendency of breakage in the last thru strains, and stresses while transferring such strains directly to the protecting layers, wherein a limited amount of yield and give is permitted.

Thus I utilize the capacity of the protecting layers, such as fibre and leather, to preserve the lateral strains on the last, as well as to preserve the top of the cone of the last from the blows and stresses of heel-nailing, sole-leveling, etc.

I believe that my invention of permanently uniting by a metal collar or washer a plurality of last protecting layers before applying the same to a last is a distinct novelty, and that my improved last, wherein a metal bearing is provided in the protecting layers and not in the thimble hole, is a distinct novelty and I wish to claim these features herein broadly.

Referring to the drawing illustrating a preferred embodiment of my present invention,

Fig. 1 is a side view of my improved last construction;

Fig. 2 is a fragmentary plan view of the protector and heel portion of the last;

Fig. 3 is an enlarged cross-sectional view on the line 3—3 of Fig. 2;

Fig. 4 is a perspective view illustrating a plurality of protecting layers united by my thimble-like tubular rivet;

Fig. 5 is a fragmentary cross-sectional view illustrating a modified form wherein the rivet extends partly into the last; and

Fig. 6 is a perspective view of the modified construction illustrated in Fig. 5.

My invention is equally applicable to any type of shoe last as well as to any style, size, or construction whether of the hinge type, block last type, two-part or three-part last construction, the invention being primarily applicable to the heel portion and to eliminate the usual thimble. These thimbles being made of high-grade and, usually, of forged metal are expensive as well as being expensive to fit and secure the same in the thimble recess bored in the last, the wood of the last being very thin at the thimble-receiving portion and, hence, being liable to split the jack under strain and use.

As shown in the drawing, a typical last for use in the manufacture of boots and shoes of the hinge type is illustrated, having a forepart 1 and heel part 2 united by any suitable pivotal and hinged construction. In the heel portion 2 is

bored the usual thimble-receiving recess 3, but instead of fitting the ordinary thimble therein I provide a metal bearing member which will take the strain of the last jack-pin at the extreme top 5 of the last, which member is preferably fitted in and thru a protecting layer, or layers, for the top of the last.

Thus I relieve the wood of the last at the top portion of the cone or heel part 2, where it is 10 thin, from breaking and strains of the jack pin.

As shown in Figs. 1, 2, 3, and 4, this metal bearing member consists of a tubular rivet 5, being of appropriate width to extend thru and be secured on both sides of the protector layer or 15 layers. As herein illustrated, I have shown two protecting layers 10 of fibre, and 11 of leather, and the tubular member 5 is fitted thru a bored opening in this protecting layer in position to be 20 in alignment with the thimble recess 3. The member 5 is fitted with an out-turned flange 6 engaging the top portion of the layer 10, and with the inner or opposite rim of the member 5 headed over or riveted, as shown at 7, thus aiding in retaining the two layers 10 and 11 firmly 25 and rigidly together, as well as giving a support to the tubular rivet or bearing member 5.

This tubular rivet 5 fitted in the protecting layers will receive the strain transmitted between the last and the jack on which the last is fitted 30 during the various shoe-making operations, particularly where heel-nailing and sole-leveling are being performed, which involve great strain. The protector layers aid greatly in preserving the thin top of the cone of the heel part of the 35 last by the wear-resistance and yield secured by the protecting layer or layers.

Similarly, this wear-resisting and yielding feature of the protecting layer, or layers, is utilized by the tubular member 5 in the lateral strains to 40 which it is subjected by the jack pin, still further freeing the wood of the heel part from breaking lateral stresses and strains, and thereby insuring long life and usefulness to my improved last construction.

Furthermore, the feature of forming a protecting layer, or layers, thus firmly united by a tubular rivet enables these protector tops to be 45 made complete and ready for attachment to the last for which they are intended. Suitable counter recesses 14-14 are bored thru the protector to receive retaining screws 15-15 which hold the protector on to the heel portion 2.

In Figs. 5 and 6 I have illustrated a modified form wherein the protecting layers 10 and 11 are united by a tubular rivet or bearing member 20 of sufficient length to extend part way into the top of the thimble hole 3. In this form of 5 rivet I provide a shouldered portion, as indicated at 21, on the rivet 20 constituting retaining means for the protector layers 10 and 11 between said shouldered portion and the flange 22 at the outer end, thus providing a thickened portion 23 to 10 fit snugly within the thimble hole 3 and retain the protector layers in alignment, in addition to the attaching screws 15.

In both forms of my invention I have provided a novel last construction wherein the thimble is 15 eliminated and a tubular rivet, collar, or bearing member only supplied to receive the jack pin of the last support to take up the wear thereof, which furthermore is largely transmitted by and thru the somewhat yielding and wear-resisting 20 layer, or layers, of the last where it is extra thin from lateral breaking strains. The projecting end of the jack pin can thus only bear against the walls of the thimble hole 12, well within the 25 body of the heel part 2 where the wood is thick and heavy and where there is no danger of breaking the last by lateral strains.

These features are of great importance in the manufacture and use of shoe lasts and will be readily appreciated by those skilled in the art. 30

I claim:

1. A last for use in the manufacture of boots and shoes, having a plurality of protecting layers for the cone of the last united by a tubular rivet said rivet being unattached to the last, and secured to said last by attachment of said protecting layers to the last. 35

2. As an improved article of manufacture, a last protector having a plurality of layers united by a tubular rivet adapted to register with the 40 thimble hole of a last, and attachable to the last independently of a thimble.

3. An an improved article of manufacture, a protector for the cone of a last, formed of wear-resisting material and yieldable material, and having fitted therethrough a tubular rivet with a flange at one end and a shoulder near the opposite end constructed and arranged to retain the protector materials together between said flange and shoulder. 45
